UNITED STATES PATENT OFFICE.

THEODOR TEISEN, OF BIRMINGHAM, ENGLAND.

FURNACE.

Application filed July 14, 1920. Serial No. 396,253.

To all whom it may concern:

Be it known that I, THEODOR TEISEN, a subject of the King of Denmark, residing at "Ewell," 52 Grove Avenue, Moseley, in the city of Birmingham, England, have invented certain new and useful Improvements Relating to Furnaces, of which the following is a specification.

This invention relates to furnaces such as annealing furnaces of a kind in which the articles or materials to be treated are passed through a long chamber in which they are first heated and afterward cooled.

The object of the invention is to provide convenient and reliable means whereby any desired temperature regulation can be obtained along the said chamber.

The invention comprises the arrangement beneath the floor of a long chamber through or around which pass the hot gases and through which pass the goods to be treated, of a collecting flue or flues communicating at intervals with the chamber. Also the invention comprises the combination with the aforesaid arrangement, of other features to be hereinafter referred to.

Referring to the accompanying sheet of explanatory drawings:—

Figure 1 is a section side elevation and Figure 2 a sectional plan of a gas fired furnace, kiln, or lehr, as constructed in accordance with this invention and adapted for the annealing of glass ware.

Figure 3 is a sectional view of the furnace.

The same reference letters in the different views indicate the same or similar parts.

In the example illustrated a long chamber *a* is adapted at one end to be heated by gas from a producer as *b* built beneath the furnace. At intervals along the chamber *a*, outlet passages *c* are provided in connection with a common collecting flue *d* arranged longitudinally below the level of the chamber. If desired, two or more collecting flues may be used. The outlet passages *c* may open into the sides or bottom of the chamber *a*, and dampers are employed to control the flow of hot gases through them. The collecting flues or flue *d* communicate with the chimney stack by one or more branch flues as *e*, and the flow of gases through these branch flues can be regulated by dampers. By this construction, hot waste gases can be withdrawn

in any desired amount at intervals along the chamber, while the cold air passing in from the left hand or exit end *f* of the furnace is prevented from causing a too sudden drop in temperature at any point; consequently, a gradual temperature gradient can be obtained within the chamber *a*, and this gradient can be varied by adjusting the outflow of the hot waste gases through the outlet passages *c* and branch flues *e*. Further in addition to obtaining any desired temperature gradient my invention enables me to ensure a uniform distribution of heat over the cross section of the furnace.

The portion *g* at the right of the furnace, immediately above the gas producer *b*, constitutes the heating chamber; the tunnel or chamber *a* aforesaid is an extension of such heating chamber.

The gases pass through flues as *h* direct to ports situated in the upper parts of the side walls of the heating chamber *g* where they are enabled to mix with sufficient air to complete the combustion, or they pass into a combustion chamber or chambers, as distinct from the heating chamber, where they are enabled to mix with the air necessary for combustion before they reach the ports opening into the heating chamber.

To ensure that the secondary combustion shall be perfect and the resulting temperature in the heating chamber *g* sufficiently high, it is advisable that the air required for combustion should be preheated, and this can be effected by drawing it in through passages situated in close proximity throughout their length to the aforesaid collecting flues or flue *d* into which the waste gases pass from the tunnel or chamber *a* as already described. Or in those cases as in the example illustrated, in which the gas producer is situated below the furnace, flues for the secondary air are provided in the side walls of the producer so that it is drawn in at about the same level as the primary air; in addition to preheating the air, the latter arrangement increases its speed and so, by facilitating the mixing together of the air and gas, assists the secondary combustion. The air passages are not shown in the drawings. These may be provided in any suitable manner as above described.

Dampers are arranged in the secondary

air flues and in the gas flues to enable the temperature in the heating chamber *g* to be controlled throughout its length.

The articles to be heated may be carried 5 on an endless conveyor belt, chain of pans, or cars passing through the chamber. An endless conveyor *i* is shown at Figure 1 of the drawings, adapted to carry the goods through the furnace from the entrance at *j* 10 at the right hand end of the furnace to the exit *f* at the opposite end. In returning from the exit to the entrance end of the furnace the conveyor passes beneath the chamber *a* as illustrated. The entrance and 15 exit are each fitted with a door arranged in any suitable manner.

It will be understood that the glass ware is raised to the desired maximum temperature as it passes on the conveyor *i*, through 20 the heating chamber *g*. From the heating chamber the goods are carried by the conveyor through the chamber *a* forming an extension of *g* as aforesaid, and during 25 transit through *a* are exposed to the hot waste gases which pass from *g* to *a* and thence to the collecting flue *d* as previously described. Such waste gases cool towards 30 the exit end of *a* and thus the goods themselves are subjected to a gradual cooling effect as is required in the annealing process.

By suitable adjustment of the various dampers the fall in temperature along the cooling chamber *a* may be varied to suit the type of glassware under treatment. It is a 35 well-known fact that in all annealing processes the fall in temperature from the maximum to a given critical point must take place at a certain maximum rate (varying with the nature of the goods dealt with) if 40 the goods are to be properly annealed. Below this particular temperature the rate of cooling may be considerably increased without damage to the goods. With my furnace it is possible to so grade the temperature 45 throughout the cooling chamber *a* that in the first place or for so long as they remain above the critical temperature the goods shall not be too rapidly cooled

while as soon as they have passed this point the rate of cooling may be increased by 50 means of air drawn in at the exit end of the chamber.

The invention is applicable to furnaces of various kinds other than annealing furnaces. Also instead of the articles passing 55 through the chamber *a* in direct contact with the hot gases, a long muffle may be employed, the articles being passed through the muffle out of contact with the gases which surround the muffle. Further, the furnace 60 may be heated in any convenient manner. Instead of gaseous fuel, pulverized or liquid fuel may be used.

Having thus described my invention what I claim as new and desire to secure by Letters Patent is:—

1. In furnaces, kilns or lehrs, the combination comprising a long horizontal cooling chamber through which are conveyed the articles to be treated, a collecting flue located beneath the floor of the chamber, a plurality of passages arranged at intervals in the side walls of the said chamber with their inlet ends at a distance above the floor of the chamber and located between 70 the chamber and collecting flue, and a branch outlet flue for discharging hot gases from the collecting flue, substantially as described.

2. In furnaces, kilns or lehrs, the combination comprising a horizontal cooling chamber through which are conveyed the articles to be treated, a collecting flue located beneath the floor of the chamber, a plurality of passages arranged at intervals 85 in the side walls of the said chamber with their inlet ends at a distance above the floor of the chamber and located between the chamber and collecting flue, and a plurality of branch outlet flues for discharging hot gases from the collecting flue at different 90 positions along the collecting flue, substantially as described.

In testimony whereof I have signed my name to this specification.

THEODOR TEISEN.
